UNITED STATES PATENT OFFICE.

SAMUEL REDPATH HEWITT, OF BELFAST, IRELAND.

COLLAR-FASTENER.

No. 869,367.

Specification of Letters Patent.

Patented Oct. 29, 1907.

Application filed July 25, 1905. Serial No. 271,197.

To all whom it may concern:

Be it known that I, SAMUEL REDPATH HEWITT, a subject of the King of England, residing at Belfast, Ireland, have invented certain new and useful Improvements in Collar-Fasteners; and I do hereby declare the following to be a full, clear, and exact description of the invention, such as will enable others skilled in the art to which it appertains to make and use the same.

10 This invention has relation to that class or kind of collar-fasteners that comprise a plate or member that is adapted to rest against the inner side of the neck-band of the shirt, and a second plate or member that is adapted to rest against the outside of the collar, the 15 two plates being connected through the intervention of means hinged or pivoted to the upper edge of the first-mentioned member and like-wise connected to the lower edge of the second member, a stud connected with one member being adapted to pass through the 20 buttonholes of the collar and neck-band and to be connected to the opposite member.

It is the object of the invention to provide improvements in the kind of collar fasteners specified that will relieve them of bunchiness, by freeing the two clasping 25 plates, when the device is applied, from any intervening means excepting the stud that passes through the button-holes.

The nature of the invention is fully and clearly ascertainable from the device portrayed in the annexed 30 drawings, forming a part of this specification in view of which it will first be described with respect to its construction and mode of use and then be pointed out in the subjoined claims.

Of the said drawings—Figure 1 is a vertical sectional view through the device when the same is in its closed position, and showing also a section through the neck band and collar with which the device is used, to illustrate the application of the various parts thereof. Fig. 2 is an elevation of the device with its members swung 40 apart, the device being arranged in a horizontal plane.

Similar numerals of reference designate similar parts or features, as the case may be, wherever they occur.

Referring now more particularly to the annexed 45 drawings, it will be seen that the so-called body portion of my fastener is composed preferably of a single piece of wire 1 bent into approximately rectangular shape thus forming an open wire frame. The end portions 2 and 3 are slightly bent or offset laterally in 50 planes at a right angle to the sides 4 and 5.

Pivotal secured in any suitable manner to the offset portion 2 of the body portion is a plate 6 provided with

an eye 7 for the reception of the stud 8 of the plate 9 when the button is in its fastened position. The stud 8 is provided with a notch or annular groove 9' in its outer portion, leaving a head 9 on its extremity to engage the perforation 7 of the plate 6 to prevent accidental disengagement of the button when in locked position. This stud is designed to be sprung or snapped into engagement with the said perforation of the plate 6. 60

When the device is to be used, the plate 6 is disposed between the neck of the wearer and the neck band 10 with the perforation 7 in said plate alining with the button-hole of the neck-band. The sides 4 and 5 of the body portion 1 are then swung downward to inclose the 65 neck band between the same and plate 6, as shown in Fig. 1. The ends of the collar are then brought together with their button holes in line with the neck-band button hole and the perforation 7 in plate 6, when plate 9 will be folded upward against said collar ends 70 in the manner shown in Fig. 1, and the stud 8 on the said plate 9 passed through the said button holes and the perforation and retained in place by means of its head 9^a, and groove 9', which is engaged in the perforation 7 of plate 6. 75

To remove the fastener it is only necessary to swing plate 9 outward when its stud 8 will be at once disengaged from plate 7 and withdrawn from the various buttonholes. The collar ends are thus released from engagement with the neck band of the shirt, and the 80 fastener may be removed from the neck-band.

By providing the stud 8 with a groove 9', a snap connection is formed between the same and the perforation in plate 6, as before stated and the formation of a post or other positive retaining means upon said plate is 85 rendered unnecessary. It will be seen therefore that the fastening means for the two plates when applied is much more simple in construction than the features for a similar purpose now in use.

What is claimed is— 90

A collar fastener comprising a body portion consisting of a substantially rectangular open wire frame, with its ends bent outward to offset the same in opposite directions; a plate provided with an aperture hingedly connected at its upper end with the upper offset end of the frame-body, and a second plate provided with a locking stud hingedly connected at its lower end with the lower offset end of said frame-body, and the end of the said stud being adapted to effect a snap engagement with the first-mentioned plate through the perforation formed in the latter. 95

In testimony whereof, I affix my signature, in presence of two witnesses.

SAMUEL REDPATH HEWITT.
